UNITED STATES PATENT OFFICE.

JOSEF HEROLD AND CARL HEROLD, OF BRUNN, AUSTRIA-HUNGARY,
ASSIGNORS TO RUNDWEBSTUHLFABRIK, HEROLD & RICHARDS, OF
SAME PLACE.

CIRCULAR LOOM.

SPECIFICATION forming part of Letters Patent No. 608,676, dated August 9, 1898.

Application filed May 6, 1897, Serial No. 635,434. (No model.) Patented in Austria January 2, 1897, No. 47/6, and March 24, 1897, No. 47/1,006; in Luxemburg March 4, 1897, No. 2,771; in Belgium March 15, 1897, No. 126,586; in England May 8, 1897, No. 5,332; in France June 2, 1897, No. 264,399; in Italy June 9, 1897, XXXIII, 44,409, and LXXXVII, 22; in Switzerland September 15, 1897, No. 13,974; in Hungary October 5, 1897, No. 9,695; in Canada November 22, 1897, No. 58,189, and in Germany February 25, 1898, No. 96,270, and March 1, 1898, No. 96,271.

To all whom it may concern:

Be it known that we, JOSEF HEROLD and CARL HEROLD, subjects of the Emperor of Austria-Hungary, residing at Brunn, Austria-Hungary, have invented certain new and useful Improvements in Round Looms; and we do hereby declare the following to be a full, clear, and exact description of the invention, such as will enable others skilled in the art to

- 10 which it appertains to make and use the same.
- This invention has been patented in the following foreign countries: Austria, issued January 2, 1897, No. 47/6, and March 24, 1897, No. 47/1,006; England, issued May 8, 15 1897, No. 5,332; Belgium, issued March 15, 1897, No. 126,586; Belgium, patent of addition, issued April 30, 1897, No. 127,581; France, issued June 2, 1897, No. 264,399; Italy, issued June 9, 1897, Reg. Gen., XXXIII, No. 44,409, 20 Reg. Att., LXXXVII, No. 22; Switzerland, issued September 15, 1897, No. 13,974; Luxemburg, issued March 4, 1897, No. 2,771; Hungary, issued October 5, 1897, No. 9,695; Germany, issued February 25, 1898, No. 96,270, 25 and March 1, 1898, No. 96,271, and Canada, issued November 22, 1897, No. 58,189.

This invention relates to a new or improved construction of circular loom by means of which a greater amount of cloth can be produced without any increase of motive power than with any of the present ordinary and circular power-loom. In our improved circular loom this is accomplished by the following arrangements: First, several shuttles 30 are at work simultaneously on the same web, and, second, the formation of the shed, the propulsion of the shuttles, and the beating up of the weft-threads are carried on without intermission.

- 40 The invention will be fully described with reference to the accompanying drawings.

Figure 1 is a front elevation, in part section; Fig. 2, a side elevation, in part section, of the loom, omitting details relating to the opening 45 of the shed and the beating up of the weft-threads to the web; Fig. 3, a vertical section

of part of loom, showing the entire arrangements for the opening of the shed, the arrangement of the shuttles, and the lever arrangements for beating up the weft-threads; 50 Fig. 4, a plan of a portion of the eccentric A with the cover off; Fig. 5, a plan view of part of the developed flanges xb' , xb^2 , and xb^3 of the eccentric; Fig. 6, a plan of the electromagnets E and shuttles S; Fig. 7, a detail views of the heddles g, and Fig. 8 a detail of the weft-guard. Fig. 9 shows the way in which the spring-rings are connected. Fig. 10 shows an outline of the heddles G and the tops of the reeds; Fig. 11, an enlarged section on line xx , 60 Fig. 10; Fig. 11^a, an enlarged section on line yy , Fig. 10; and Fig. 12, the toothed flanges R, the flange Rx with the eccentric flanges xb' , xb^2 , xb^3 , and the levers bl' , bl^2 in outline.

By reference to the drawings the most important arrangements of our circular loom are seen to be, first, the opening of the shed; second, the shuttles; third, the lever arrangement for beating up the weft-threads to the web; fourth, the weft-guard, and, fifth, the 70 driving arrangements of same.

The shaft W', journaled in the bearings l^3 and driven by the pulley P, Figs. 1 and 2, transmits its motion, by means of the beveled wheels K² K, to the vertical shaft W. The latter is journaled at one end in the collar l' in the cross-piece T³ and at the other end in the collar l^2 in the bell-shaped piece H⁶ on the cross-piece T³, and the rings above these collars l' , l^2 serve as supporting-surfaces. 80

On shaft W, underneath the cross-pieces T', the boss N is fixed, and on this the electromagnets (the number of which in the present case is four, Fig. 6) are secured. These electromagnets receive the current from some 85 source of current through the intermediary of a sliding contact located on, but insulated from, the shaft w. The contact consists of a collar m³, made of insulating material—such as wood, hard rubber, ebonite, or the like—90 upon which two brass rings m⁶, m⁷ are fixed. A stationary brass spring m⁴ rubs against

each of these rings. The wires $m' m^2$, leading from the source of current, are connected with the supports m^3 of these contact-springs. From the rings conducting-wires $m^8 m^9$ lead 5 to the successive magnet-coils E. On the cross-pieces T the bearings r' of the rollers r , revolving on the pin r^2 , are fixed, and these rollers project into the groove r^3 of the toothed flange R, which they support and enable to 10 run easily and steadily, Fig. 3. Instead of roller-bearings for the toothed flange ball-bearings may be advantageously used.

The vertical shaft W^2 rotates in the bearings $l^4 l^5$, Fig. 2, fixed on the cross-pieces $T^4 T$, 15 and the toothed wheel Z, firmly fixed upon the vertical shaft W^2 , engages with the toothed flange R, the effect of which arrangement is to cause the toothed flange R to make the same number of revolutions as the shaft W . 20 Shaft W^2 is driven by means of the beveled wheels $K' K^3$ from shaft W' , so that shaft W , shaft W^2 , and the toothed flange are all interconnected. The warp is carried from the 25 warp-beams KB, (the number in the present case being four,) weighed in the usual way over the beams C C' C² to the heddles g, and the warp-threads $n' n'$ must, in order to be properly distributed, first pass the cross-rings $h' h'$. The heddles, Fig. 7, which have an eye 30 g' in the center, and the number of which corresponds to the number of the warp-threads, are fitted radially to the shaft W . One end of the heddles is deflected downward at a right angle and carries a roller gr, while the other 35 end, on account of being supported radially, is suitably flattened. The deflected ends of the heddles g are carried into the suitably-shaped grooves $X^5 X^6$ of the rings $X^2 X^3$. The number of these eccentric-rings, on the 40 topmost of which a cover X' is put and which are interconnected by screws, corresponds to the warp-and-weft arrangement of the web, and in the present instance two eccentric-rings are required. As shown in Fig. 4, the 45 grooves $X^5 X^6$ of the superimposed eccentric-rings $X^2 X^3$ intersect each other, and the number of these intersections must correspond with the number of the shuttles. The undermost eccentric-ring X^3 is firmly 50 connected by the arms Y and the ring X^4 by means of screws with the toothed flange R. At the other ends the heddles g are carried between the vertical metal plates B² of the 55 reed-flanges B B', Figs. 10, 11, and 11^a, which are placed upon the spring-rings $b' b^5$ and kept apart from each other by intervening pieces. By this means the heddles are prevented from following the rotary motion of the eccentric-rings $X^2 X^3$. The heddles g 60 slide on ring b^4 or over the little pulleys or ring b^5 between every two metal plates. One portion of the metal plates B' is lengthened at the top and is there fastened by screws or rivets to the shoulders D² D³ of the bearing-pieces D D', the former of which is screwed 65 to the cross-pieces T' and the latter to the belt-shaped pieces a⁶. One portion of the metal

plates B² is lengthened at the bottom and connected by the metal pieces b⁶ with the cylinder-casing f, thus providing a firm bearing for the latter. The loose temple-ring C, which is held on the lower end of the shaft W by a ring, is unaffected by the rotary motion of the shaft W and has a groove n² on the upper side, in which an isolated contact-ring is fixed. Further, the temple-ring C carries a cylinder-casing f, made of non-magnetic material, which on one side serves as a supporting-surface for the warp-threads pressed inward by the shuttles S and on the other side prevents the shuttles being completely drawn to the electromagnets E. The latter are shaped in such a way that they can easily move inside the cylinder-casing f. 70 75 80

The shuttles S, which are made of some light material—such as wood, paper, &c.—are suitably adapted in shape to the box, which is round and at the bottom runs to a point, and are provided with a cavity e for the reception of the cop or spool. On the 85 side which is turned to the casing f the shuttles are fitted with a metal plate (iron) sb for magnetic effect and run with their pairs of rollers sr' and sr over the warp-threads adjacent to the casing f and with their pair of rollers sr² on the ends A⁵ of the levers $l^2 l^3$, projecting into the box. Through the hole S', Fig. 6, the weft-thread is carried over the 90 guide-pin O' to the web.

On the inner side of the toothed flange R 100 a flange Rx is fixed, on which the pieces xb' xb^2 xb^3 , forming the eccentric, are screwed. On the cross-pieces T the brackets D² are 105 fixed under the nether flange xb', and on these brackets are screwed the plates Y, which are connected with the bearing-pieces q of the levers $l^2 l^3$. To the holes of the radially-placed bearings q a spring-ring M is fixed, on which the bent levers bl² are loosely placed. The arms a' of the levers $l^2 l^3$, each provided 110 with roller a², project into the curved groove 1, formed by the flanges xb' and xb³, and in the same way the arms a³, fitted with rollers a⁴ of the levers $l^2 l^3$, project into the winding-groove 2, (see also Fig. 5,) formed by the 115 flanges xb² and xb³. On the other side the flat arms a⁵ of the levers $l^2 l^3$ project underneath the shuttles S and above the temple-ring C, between the warp-threads, into the 120 box.

In order to stop the rotary loom when a weft-thread is broken or has come to an end, a weft-guard is placed on the standard S under the belt-pulleys P and Q. This guard, Figs. 2 and 8, consists of a steel spring Gf, 125 fixed to the standard S, into the slit se, of which the pin Gb in the lower end of the fork G, pivoted into the bearing Ga, is carried. The steel spring Gf intersects the slot sl' of the plate st on the standard S, round the pin sl² of which the angular lever hs is provided. The arm hs' of this angular lever projects on one side into the opening of the electromagnetic bobbin fixed on the plate st, while 130 135

the steel spring Gf comes into contact with its curved lower end hs^2 when the loom is started. The coil sE is put in the circuit in the following manner: Conducting-wires 3 and 4 branch off, respectively, from each of the wires $m' m^2$, leading from the source of current to the electromagnets E . These wires 3 and 4 lead to the levers bl^2 , which are electrically connected by the manner in which 10 they are mounted and to the binding-post 1' of the coil sE . The other binding-post 2' of said coil is connected by the conducting-wire 5 with the insulated copper ring ce in the groove n^2 of the temple-ring C . The stroke 15 of the bell-crank or angular lever hs is arrested by the pin st^4 , and the angular lever hs is held in the position shown in the drawings by the spring sf .

The rotary loom works as follows: When 20 the warp-threads $n n'$ are drawn in the manner shown and described, the shed formed by the heddles g , and the shuttles S put into the box, the magnet E is energized by a current that passes through the wire m' , the upper 25 spring m^4 , the ring m^6 , the wire m^8 , all the magnet-coils E , the wire m^9 , the ring m^7 , the lower contact-spring m^4 , and the wire m^3 back to the line. During the rotation of the shaft w the stationary contact-springs slide without 30 interruption against the rings $m^6 m^7$, so that the magnets E are constantly energized, and the shuttles are carried along with the motion of the shaft W by the continuously-operating attraction of the electromagnets, 35 which causes them to run along the race and insert the weft-threads. At the same time the position of the shuttles S and of the eccentrics $X^2 X^3$ is so arranged that behind each shuttle at the spot which it has just traversed 40 an immediate change of shed takes place, which is effected in the present arrangement by the deflected ends of the heddles g in the inner part of the groove X^5 passing into the outer part of the groove X^5 , by which means 45 the warp-threads n , hitherto forming the right part of the shed, are carried outward and now form the left part of the shed. (Refer to Figs. 1 and 2.) At the same time the warp-threads n' also change their position as the deflected 50 ends of the heddles g are carried from the outer part of the groove X^6 to the inner part of the same.

As in the accompanying illustration, the groove-courses $X^5 X^6$ intersect each other 55 four times, the shed is divided into four parts, and the warp-threads $n n'$ run in the third division of the shed in exactly the same way as the first, whereas in the second and fourth divisions of the shed they are reversed—that 60 is to say, if, for example, the warp-threads form the right part in the first and third divisions of the shed they form the left in the second and fourth, and so on. It should be mentioned here that the number of eccentric-rings $X^2 X^3$, that of the intersections of the 65 grooved courses $X^5 X^6$ and that of the shut-

ties, are regulated according to the nature of the material required.

As soon as the weft-threads have been carried over the lever-arms a^5 they require beating up to the web, which is effected by the arm a' of the lever bl^2 coming in the first place into the descending curve of the groove 1, Fig. 5, when the lever bl^2 is turned in the direction of the arrow, Fig. 3. The latter 75 carries the lever bl^2 with it and throws the latter's arm a^5 out of the shed. The relative positions of the downward curves of the grooves 1 and 2 are now such that after the commencement of the lever motion described 80 the arm a^3 of the lever bl^2 comes into the curve of the groove 2 when the lever bl^2 is turned in the direction of the arrow 2, Fig. 3. The lever-arm a' has in the meantime entered the straight part of the groove 1 and turned the 85 levers $bl^1 bl^2$ in the direction of the arrow 3, Fig. 3, when the arm of the latter again enters the shed above the inserted weft-thread, as its arm a^3 is still in the curve of groove 2. The lever-arm a^3 now begins to pass the ascending part 2' of the curve in the groove and thus turns the lever bl^2 back into its original position, and consequently its arm a^5 beats up the last shot to the web and leaves the way clear for the following shuttle. As 90 there are always a large number of the radially-placed levers $bl^1 bl^2$ a part of the lever-arms $a' a^3$ always pass the curves of grooves 1 and 2, so that the beating up of the weft is going on continuously. The curves of the 95 grooves 1 and 2 are so arranged that the weft is immediately beaten up by the lever-arms a^5 when, after a shot has been inserted, a change of shed has taken place. Of course the position of the intersections of the grooves $X^5 X^6$ of the eccentrics $X^2 X^3$ and the curves of the grooves 1 and 2 of the flanges $Xb' Xb^3$ Xb^3 can be so arranged that the beating up of the weft to the cloth takes place first and the change of the shed afterward. The curves 100 of the grooves 1 and 2 then, from the intersections of the grooves, courses $X^5 X^6$ of the eccentrics $X^2 X^3$, and a double beating of the lever-arms A^5 on the web can easily be attained by double bends in the grooves 1 and 2. 105

The web passes from the temple-ring C between the tension-rollers dd^4 , the axles $d' d^5$ of which revolve in the bearings $d^2 d^3$. The roller d is driven from the main shaft W' by means of the strap-pulleys pp' , axle W^3 , 110 scroll O , and the scroll-wheel t , fastened on the roller-axle d' , which engages with the scroll. Motion is imparted to the squeezing-roller d^4 by the shaft d' through the agency of the toothed wheels dz on the axles $d' d^5$, 115 which engage with each other. After the tubular web has left the rollers dd^4 it wraps itself automatically in consequence of its friction against roller d on roller L , which revolves on the brackets ii . 120

The stoppage of the loom when the weft-thread breaks or a spool becomes empty is 125

effected by the lever-arms A^5 falling by their own weight and that of the following shuttle into the opening formed near the end of the weft-thread and coming into contact with the 5 ring ce , Fig. 3, when the piece hs' of the angular lever hs is drawn into the spool sE , Fig. 8, and the spring Gf is released from the nozzle hs^2 . The spring gp moves in consequence of its elasticity in the direction of the arrow, 10 Fig. 2, thus turning the fork G , which pushes the strap from the pulley P to the loose pulley L .

What we claim as our invention, and desire to secure by Letters Patent, is—

- 15 1. In a circular loom, the combination with an upright shaft, of one or more electromagnets carried thereon, an upright stationary casing concentric with said shaft, and surrounding said magnets, shuttles bearing 20 against the outside of the casing, and levers for beating up the weft and serving as a track for supporting said shuttles, substantially as described.
- 25 2. In a circular loom, the combination with an upright shaft, of one or more electromagnets carried thereon, an upright metallic casing concentric with said shaft, and surrounding said magnets, weft-beating levers radial to the shaft and arranged near the bottom of 30 the casing, and shuttles having horizontal rollers to bear against the casing and vertical rollers to rest and roll on the levers, substantially as described.
- 35 3. In a circular loom, the combination with an upright shaft, of one or more electromagnets carried thereon, a stationary casing with- 40 in which said magnets rotate, radial weft- beating levers, adjacent to the lower end of said casing, magnetic shuttles bearing against the outside of the casing and resting on the levers, radial heddles above said levers, and 45 annular cams rotating synchronously with the electromagnets and engaging with the ends of the heddles, substantially as described.
- 50 4. In a circular loom, the combination with an upright shaft, of a ring mounted to rotate concentric with said shaft, and having peripheral teeth, a second shaft carrying a pinion meshing with said teeth, a main horizontal shaft carrying means for driving both of 55 said shafts, annular grooved cams carried on said ring, radial heddles and weft-beating levers engaging with the grooves in said cams, electromagnets carried by the central shaft, and shuttles adapted to be propelled thereby, said shuttles resting on said weft-beating levers, substantially as described.
- 60 5. In a circular loom, the combination with means for propelling the shuttles, of two concentric series of stationary upright reeds, rings passing through said reeds, rollers on said rings, between said reeds, and a series of radial heddles passing between said reeds and supported by said rings and rollers, substantially as described.
- 65 6. In a circular loom, the combination with means for propelling the shuttles, of two con-

centric series of stationary upright reeds, spring-rings passing through said reeds, rollers on said rings separating said reeds, and 70 a series of radial heddles arranged in two sets, upper and lower, each heddle passing between two reeds, substantially as described.

7. In a circular loom, the combination with an upright shaft, of electromagnets carried 75 thereon, two sets of stationary reeds concentric with each other and with the shaft, heddles movable radially between said reeds, a stationary casing inclosing said electromagnets and supported from the inner set of 80 reeds, and magnetic shuttles resting against the outside of said casing, substantially as described.

8. In a circular loom, the combination with an upright shaft, of electromagnets carried 85 thereon, two sets of stationary reeds concentric with each other and with the shaft, heddles movable radially between said reeds, a stationary casing inclosing said electromagnets and supported from the inner set of 90 reeds, an annular temple attached to the bottom of the casing, and magnetic shuttles resting against the outside of said casing, substantially as described.

9. In a circular loom, the combination with 95 a series of weft-beating levers radially arranged, of an annular temple located adjacent to the ends of said levers, an insulated contact-ring carried by said temple, and an electrically-controlled stop-motion having its 100 terminals connected respectively with said levers and with said ring, substantially as described.

10. In a circular loom, the combination with a series of radial weft-beating levers, of an 105 annular temple having a groove in its upper surface, and arranged beneath the ends of said levers, an insulated ring carried in said groove, and an electrically-controlled stop-motion having its terminals connected respectively with 110 said levers and with said ring, substantially as described.

11. In a circular loom, the combination with a radial series of weft-beating levers, of a contact-ring arranged adjacent to the ends of 115 said levers, a spring-actuated lever serving as a belt-shifter, a plate having a slot in which the said lever can move, an angular latch having one end projecting across said slot, an electromagnetic solenoid into which 120 projects a core attached to said latch, and electrical connections between the solenoid, the radial levers and the contact-ring, whereby when a weft-thread breaks one of the levers will come in contact with the ring and 125 thereby close the circuit through the solenoid, causing the latch to be withdrawn and allowing the belt-shifter to operate, substantially as described.

12. In a circular loom, radially-arranged 130 weft-beating levers each consisting of an elbow-lever, a bent lever pivoted to one arm of the elbow-lever, one end of the bent lever being adapted to enter between the warp-

threads, means for vibrating the elbow-lever to carry the bent lever back and forth radially, and means for vibrating the bent lever up and down, substantially as set forth.

5 13. In a circular loom, the combination with a set of radially-arranged levers bl' and bl'' mounted on stationary supports D_2^1 and having rollers a^2 , a^3 , of the rings xb^1 , xb^2 , xb^3 , whose adjacent edges form cam-grooves engaging with said rollers, and means for re-

volving said rings concentric with the levers, substantially as described.

In testimony whereof we affix our signatures in presence of two witnesses.
